UNITED STATES PATENT OFFICE.

MAURICE LACHMAN, OF NEW YORK, N. Y., ASSIGNOR, BY MESNE ASSIGNMENTS, TO BETHLEHEM STEEL COMPANY, OF BETHLEHEM, PENNSYLVANIA, A CORPORATION OF PENNSYLVANIA.

METAL WHEEL.

1,363,519.

Specification of Letters Patent. Patented Dec. 28, 1920.

Application filed March 14, 1919. Serial No. 282,592.

To all whom it may concern:

Be it known that I, MAURICE LACHMAN, a citizen of the United States, and a resident of New York, in the county of New York 5 and State of New York, have invented certain new and useful Improvements in Metal Wheels, of which the following is a specification.

My invention relates to that class of 10 wheels in which a metal disk or plate is employed, said disk or plate being formed in one piece with a hub part, rim part and an intervening web portion answering to the spoke part of the wheel.

15 My invention is designed particularly for use in the construction of wheels wherein the separate rim or felly is secured to the metal disk or plate.

The object of the invention is to provide 20 a suitable support or bearing for the rim and likewise to enable the wheel to be cheaply and easily constructed from metal plates and sections of bar steel of any of the usual commercial forms.

25 To these ends my invention consists essentially of a sheet metal disk or plate forming the spoke portion of the wheel and having notches at its edge which receive and hold rim supporting bars arranged therein

30 transversely of the plane of the disk and held therein against movement either circumferentially or laterally of the disk.

In carrying out my invention I prefer to use those shapes of bar iron which generally 35 may be described as angle bars, by which term I include T, L and other shapes.

My invention consists further in features 40 of construction and manner of interlocking the rim supporting bars in the disk or plate as hereinafter more particularly described.

In the accompanying drawings:

Figure 1 is a side elevation of a construction embodying my invention.

Fig. 2 is a transverse section on the line 45 2—2 Fig. 1.

Fig. 3 shows a portion of the notched edge of the disk with one of the rim supporting bars in section.

Fig. 4 shows one of the transverse sup- 50 porting bars in a preferred form.

Fig. 5 is an elevation of a modified form of the construction embodying my invention in which L bars are used in place of T bars.

Fig. 6 is a vertical cross-section on the 55 line 6—6 of Fig. 5.

Fig. 7 shows a portion of the notched edge of the disk, Fig. 5, with one of the supporting bars shown in section.

Fig. 8 shows one of the supporting bars of the construction Fig. 5 detached. 60

Referring to the drawings, 1 indicates the disk or plate of sheet metal having rim and hub parts connected by an intermediate web or spoke portion, the hub part being perforated as at 3 for the axle or for the attachment of the hub and bearings. 4 indicates a separate metal rim or felly for the wheel which is carried on the edge of the disk 1 and is supported in position and reinforced against collapse by the load by means of 70 transversely extending bars 5.

In Figs. 1 to 4 inclusive each one of said bars consists of a section of bar steel or other metal which is of T form in cross-section, the head of the T being utilized to 75 form a bearing for the rim and being secured to said rim by suitable means, as for instance by spot welding, while the upright or stem of the T reinforces the bar as a support for the rim and is preferably 80 notched as indicated at 6 to engage the plate 1 and be held thereby against lateral displacement in obvious manner by the interlocking of the bar and disk thus afforded.

As shown in Fig. 3 the notches 7 in the 85 edge of the disk are suitably shaped to receive the sections of metal bar constituting the supporting brackets for the rim and when the bar is seated in said notches 7 it is securely held thereby against displacement circumferentially of the disk. Preferably the notching at 7 is deep enough to allow the head of the T or surface which receives the rim to be flush with the circumferential edge of the disk. 90

Obviously the disk may be located centrally of the supporting bars to give the same amount of overhang of rim with respect to the plane of the disk 1. When the bar is sunk in the edge of the disk, as described, to be flush with the edge thereof, other notches 6' may be provided in the head of the T section which will engage and interlock with the disk to assist in holding the bar against displacement transversely. 95

Obviously further, the disk might be located to one side of the center of the bar, in which case the rim would overhang the web portion of the wheel more on one side than on the other. This modification in the dis- 110

position of the rim and disk may be readily secured by changing the location of the notches 6, 6'. Also more than one disk may be employed, in which case all that is necessary is to properly position the notches 6, 6'.

In Figs. 5 to 8 inclusive I illustrate a modification in which the supporting bars may be sectioned of an L-shaped or V-shaped metal bar. In this instance the 10 edge of the disk or plate is suitably notched as indicated in Fig. 7, to allow the angle of the bar to enter the edge of the disk and to hold the bar against displacement circumferentially of the disk.

15 To hold the bar against displacement transversely of the disk it is provided with the notches 6, 6' as before, the notches 6 interlocking with the plate 1 at the bottom of the notch in its edge and the notches 6' interlocking with the disk by the projections left on the edge of the disk at opposite sides of the notch therein. In this modification as will be seen, the two edges of the angle bar afford an extended bearing for the rim 25 both laterally and circumferentially on the wheel. If desired the open ends of the bar 5 may be closed in any suitable manner.

As indicated in Fig. 4, the corners of the 30 supporting bars or brackets may be rounded off as at 10 to avoid the presence of projecting sharp corners on the faces of the wheel.

What I claim as my invention is:—

1. In a wheel of the character described, a metal disk having an edge notched to receive transversely extending rim-supporting bars, said bars being notched to interlock with the rim and be held against movement laterally of the disk.

2. In a wheel of the character described, 40 the combination with a disk having a notched edge, transversely disposed rim-supporting bars seated in said notches, a rim bearing upon and secured to said bars and means for holding the bars against displacement laterally of the disk.

3. In a wheel of the character described, 45 the combination of a notched disk and

notched supporting bars supporting the rim of the wheel, said notches operating to hold the bars against lateral and circumferential 50 displacement on the disk.

4. In a wheel of the character described, the combination of a disk, transverse T-shaped rim-supporting bars carried on the edge of the disk, said disk and bars being 55 provided with notches coöperating to hold the bars against both lateral and circumferential movement on the disk.

5. In a wheel of the character described, the combination of a disk notched at its 60 edge, T-shaped metal bars seated in said notches with the heads of the T's flush with the circumferential edge of the disk, a rim fastened to the heads of said bars and means for holding said bars against displacement 65 laterally of the disk.

6. In a wheel of the character described, the combination of a disk notched at its edge, T-shaped metal bars seated in said notches with the heads of the T's flush with 70 the circumferential edge of the disk and a rim fastened to the heads of said bars, said bars being also notched to interlock with the disk and be held against lateral displacement thereof.

7. In a metal wheel of the character described, the combination with a metal disk having a notched edge, of transverse supporting brackets for the rim notched to interlock with the disk.

8. In a metal wheel of the character described, the combination of a metal disk notched at its edge, and rim-supporting brackets formed of angle iron and suitably notched to interlock with the edge of the 85 disk.

Signed at New York in the county of New York and State of New York this 12th day of March A. D. 1919.

MAURICE LACHMAN.
